গুরুত্বপূর্ণ বিষয়

UNITED STATES PATENT OFFICE.

CHARLES ROBERT BRAWNER, OF LOS ANGELES, CALIFORNIA.

LUGGAGE-FASTENER.

1,270,921.

Specification of Letters Patent. Patented July 2, 1918.

Application filed May 8, 1917. Serial No. 167,194.

To all whom it may concern:

Be it known that I, CHARLES R. BRAWNER, a citizen of the United States, residing at Los Angeles, in the county of Los Angeles 5 and State of California, have invented a new and useful Luggage-Fastener, of which the following is a specification.

This invention relates to devices of the character designed for fastening luggage 10 or parcels in place as, for instance, on the step or running board of a vehicle.

An object of this invention is to produce a device of this character of the greatest simplicity and inexpensiveness of construction, also one in which it will be easy to fasten the luggage.

This device is an improvement on my former invention of parcel holder patented June 6, 1916, No. 1,185,763. In the former 20 patent notches and a detent were provided to prevent relative movement between the bar and the adjustable U-shaped clamping member. In this present device other means are provided to prevent movement of the 25 clamping member away from the bar, said means being formed by the strap which encircles the luggage.

Other objects and advantages will appear in the subjoined detail description.

30 The accompanying drawings illustrate the invention:

Figure 1 is a side elevation of a vehicle having two of the newly invented devices in place on the running board thereof, luggage held by the fasteners also being shown.

Fig. 2 is an enlarged side elevation of one of the luggage fasteners shown in Fig. 1, the strap being in the luggage-holding position.

40 Fig. 3 is an enlarged plan view of the luggage fastener shown in Fig. 2, portions of the strap being broken away to contract the view.

Fig. 4 is a perspective view of the luggage fastener, the strap being omitted for clearness of illustration.

Fig. 5 is a side elevation analogous to Fig. 2 of a modification of the invention.

Fig. 6 is a detail partly in section on line 50 indicated by x^6 — x^6 , Fig. 5.

Fig. 7 is an enlarged detail of the outer end of the adjustable clamp and adjacent parts in Fig. 5, the buckle and abutment being shown in section.

55 There is provided a bar 1 which is preferably flat as shown and is designed to rest

upon a support such, for example as the running board A or any other suitable part of a vehicle to which the luggage is to be secured. One end of the bar 1 is upturned 60 and provided with an eye 2 and the opposite end of the bar has formed integral therewith a depending L-shaped clamping member 3 which is designed to coöperate with the bar 1 when the device is clamped upon 65 the vehicle. One arm portion of this L-shaped member 3 is disposed in parallel relation to the bar 1 and at the free end of said arm portion is carried an adjustable clamping screw 4. The screw 4 is formed 70 with an enlarged head 5 designed to engage the under face of the running board A or other portion of the vehicle or support to which the device is attached so as to clamp the bar 1 thereto. The end of the screw 75 opposite the head is provided with a handle 6 whereby the screw may be readily turned to tighten it against the running board.

Extending from opposite edges of the bar 1 at the end thereof having the clamping member 3 are ears 7, the plane of said ears coinciding with the plane of the bar 1 so that the upper face of the bar 1 is flat from the upturned end to the end having said ears. These ears 7 slidably receive the arms 80 of an extensible U-shaped clamping member 8 which may be formed of heavy wire or the like. The clamping member 8 is shiftable endwise relative to the bar 1, and the plane in which the arms of said clamping member lie coincides with the plane of 85 said bar. The web portion 9 of this clamping member 8 is directed upwardly at right angles to the arm portions to form an inverted U-shaped luggage-engaging abutment. The upturned end 10 having the eye, 90 2 also forms a luggage-engaging abutment.

To the abutment 9 of the clamping member 8 is secured a strap 11 formed of webbing, leather or other suitable material and 100 said strap is rove through a buckle 12 and thence through the U-shaped abutment 9 so as to form a loop 13 between the buckle and the abutment. From the abutment 9 the strap extends lengthwise of the upper face 105 of the bar 1 in a straight portion 14 which rests upon and substantially covers the upper face of the bar thus insuring against marring of the luggage or parcels held in the device. From the straight portion 14 110 the strap 11 passes through the eye 2 of the upturned portion 10 and from said eye the

strap passes along one edge and the top of the luggage, indicated at B in Fig. 1, and passes along the opposite side of the luggage and thence through the buckle 12 so as 5 to be engaged by the tongue 15 of said buckle in a manner well understood.

In practice one or more of the devices will be clamped upon the running board A of the vehicle as shown in Fig. 1 so that 10 the bar 1 will extend transversely of the running board, or upon any other suitable part of the vehicle and the luggage B or other articles to be held will be placed upon the bar 1 against the abutment 10 so that 15 the weight of the luggage aids in holding the bar in place. The clamping member 8 having previously been drawn out will be forced in so that the abutment 9 will engage the luggage. At the same time the strap 11 20 will be drawn up tight and fastened in the buckle 12 in a manner well understood.

It is noted that when the luggage is thus fastened in place the tendency of the pull of the strap 11 is to force the abutment 9 25 toward the bar 1 and that said abutment cannot be moved away from the luggage because of the portion 14 of the strap being rove through the clamping member and through the eye 2. Thus the clamping 30 member 8 is held without the provision of the notches and detent disclosed in the above noted patent. Thus not only is this device simpler and cheaper to manufacture than the former patented device but the adjustment thereof to the luggage to be fastened is much more easily and quickly accomplished.

It is understood that changes of construction from that described above may be made 40 within the spirit and scope of the invention as defined in the appended claims.

In the form of the invention in Figs. 1 to 4 the strap 11 is not fastened to the buckle 12 but is only fastened to the abutment 9 5 so that the buckle is slideable along the strap and shortening of the adjustable loop 13 can occur to take up the slack in the strap por-

tion 14 when the clamping member 3 is pushed inward toward the luggage.

In the form of the invention in Figs. 5 50 to 7 the strap 11 is fastened to the buckle 12 by reason of it being fast in the loop 13 which is secured on both sides of the abutment 9 by rivets 16 so that slack can only be taken up in the strap 11, when the clamping member 3 is pushed inward toward the luggage, by drawing the strap 11 through the eye 2 to take up the slack in the strap portion 14. Though generically the invention covers this form as well as that in Figs. 60 1 to 4, the latter is preferable.

I claim:

1. A luggage fastener comprising a flat bar having an eye at one end and having ears extending laterally from its edges adjacent the opposite end, a clamping member having straight arms shiftably engaging the ears, means connected with the bar to fasten the bar to a support, a buckle, and a strap rove through the clamping member between 65 the arms thereof and through the eye and lying on the upper face of the bar and fastened to the clamping member and forming a loop rove through the buckle.

2. A luggage fastener comprising a flat 70 bar having an eye at one end and having ears extending laterally from its edges adjacent the opposite end, a clamping member having straight arms shiftably engaging the ears, means connected with the bar to fasten the bar to a support, a buckle, and a strap rove through the clamping member between 80 the arms thereof and through the eye and lying on the upper face of the bar and fastened to the clamping member and forming a loop rove through the buckle, the buckle being slideable along the strap.

Signed at Los Angeles, California, this 2d day of May, 1917.

CHARLES ROBERT BRAWNER.
